UNITED STATES PATENT OFFICE.

GEORGE WESTINGHOUSE, OF PITTSBURG, PENNSYLVANIA, ASSIGNOR TO THE WESTINGHOUSE MACHINE COMPANY, A CORPORATION OF PENNSYLVANIA.

ELASTIC-FLUID TURBINE.

No. 880,847.

Specification of Letters Patent.

Patented March 3, 1908.

Application filed August 23, 1904, Serial No. 221,361. Renewed September 18, 1907. Serial No. 393,461.

To all whom it may concern:

Be it known that I, GEORGE WESTINGHOUSE, a citizen of the United States, and a resident of Pittsburg, in the county of Allegheny and State of Pennsylvania, have invented a new and useful Improvement in Elastic-Fluid Turbines, of which the following is a specification.

This invention relates to elastic fluid turbines, and more particularly to turbines applicable to marine propulsion and designed to act as reversing engines.

The object of this invention is to produce a reversing turbine in which the fluid, which for the sake of clearness will be hereinafter referred to as steam, is worked as described in an application made by me for Letters Patent, Serial Number 219,731, for improvements in elastic fluid turbines.

20 A further object of this invention is to provide certain improvements in the construction and arrangement of parts which are equally applicable to turbines of various types.

25 These and other objects I attain in the turbine described in this specification and illustrated in the accompanying drawings throughout which corresponding elements are denoted by like characters.

30 Figure 1 is a longitudinal sectional view of a turbine embodying this invention: Fig. 2 is a cross sectional view taken on the line DD of Fig. 1: Fig. 3 is a view partially in developed section and partially in plan taken on lines AA and BB in Fig. 2: Fig. 4 is a view in cross section taken on line CC in Fig. 3; Fig. 5 is a longitudinal section of a reversing valve, Fig. 6 is a partial longitudinal section illustrating a detail of the turbine.

40 The turbine consists of a casing 5 divided on the horizontal plane through its axis, as is now common practice, whereby the upper half may be readily lifted off. The lower half of the casing is provided with bearing supports 6, within which suitable bearings carrying the turbine shaft 7 are located.

Near the center and extending circumferentially of and exteriorly to the casing, two steam conduits 8 and 9 are located.

50 Conduit 8 is adapted to carry the steam to the primary or "ahead" portion of the turbine while conduit 9 carries the steam to the secondary, reversing or astern portion of the turbine.

55 A spirally extending partition 10 separates

the two conduits, and this partition is spirally formed in order to allow the nozzle segments (hereinafter referred to) for the ahead and astern portions to be arranged in a line around the turbine.

60 Exhaust chambers 11 are provided at each end of the turbine and exhaust ports 12 will lead the exhaust from each end to a common condenser, whereby when either the ahead or astern portion of the turbine is operating under steam the other portion will be rotating in a vacuum, as is now common practice.

Bolted or otherwise suitably secured against the inner periphery of the casing and below the center line of the steam conduits 8 and 9 are a plurality of nozzles formed in a ring 13 that is cut in halves and is provided with ahead steam spaces 14 and with astern steam spaces 15, each communicating with its steam conduit by means of its steam channel 16 with which it registers. Each of these nozzle segments is provided with radially or outwardly extending members or blades 17 of such contour in cross section that steam nozzles are formed between them. The outer face of each of these segments and the ends of the blades 17 are machined to conform to the inner periphery of the turbine casing, and said casing forms one wall of the nozzles.

65 It will be understood of course that the ahead and astern nozzles discharge from their steam spaces in opposite directions.

The inner peripheries of segments 13 are provided with rows of annular leaves or flanges which interleave with corresponding grooves in that portion of the turbine rotor adjacent thereto. This form of seal comprising interleaving flanges is so well understood in the art that further description is unnecessary.

70 The portion 18 of the rotor lying directly below or inside of this fluid seal is provided with an annular channel or chamber 19, which lies below or inside of the center of the middle of the fluid seal whereby fluid which leaks through said seal from either direction will collect in said chamber; and extending through said seal and the ring 13 at any convenient portion 20 of the seal a steam channel 21 communicating with said steam chamber 19 is adapted to conduct the leakage steam to a portion of the turbine where it can be utilized in doing work. The passage 21 is provided with a valve 21^a which is capable of 105

110

throwing it into communication with either a passage 21^b or a passage 21^c. The passage 21^b communicates with a working portion of the ahead turbine and the passage 21^c communicates with a working portion of the astern turbine.

It will be seen that if the interleaving flanges and grooves offer sufficient resistance to the passage of steam, and if the fluid chamber 19 and the channel 21 are of sufficient area to permit free passage of the steam therethrough, and the steam is led to a portion of the turbine where the pressure is relatively low, that the steam will flow through this chamber and channel in preference to passing through the side of the interleaving flanges of that end of the turbine running in vacuum. By this means, when the turbine is operating "ahead" some of the steam which otherwise would leak to the exhaust is partially utilized in doing work in the ahead portion of the turbine and when the turbine is operating astern the steam from the chamber 19 is utilized in doing work in a portion 25 of the astern turbine.

The turbine rotor adjacent to the steam nozzles is provided with a plurality of rows of blades 22 which coöperate with rows of stationary vanes 23 carried by the turbine casting.

The steam issuing from the final rows of moving blades 22 may be worked in any satisfactory manner but in the construction illustrated it is preferable to work the steam as described in the application hereinbefore referred to.

A thrust bearing 24, of any suitable design is utilized for taking up the unbalanced end thrust of the turbine shaft 7 which will be 40 connected to the propeller shaft to be driven.

It will be understood that to a great extent the end thrust imparted to the turbine shaft by the propeller will be counteracted by the end thrust of the turbine itself which will be 45 in the opposite direction to the propeller end thrust, and this will be true with the turbine rotating in either direction.

As indicated in Fig. 5, a steam chest 25 of any suitable design will connect with the 50 ports 26 and 27 for the ahead and astern steam inlets, and any suitable valve such as a piston valve 28 may be utilized in connection with said steam chest whereby by a movement of said valve in either direction 55 the steam will be cut off from one inlet and admitted to the other.

Having thus described this invention what I claim as new and useful and desire to secure by Letters Patent is:—

60 1. In an elastic fluid turbine, an ahead portion, an astern portion, a seal between said portions and means whereby the fluid escaping from either of said portions through said seal is conducted to an operative point 65 of the ahead portion.

2. In an elastic fluid turbine, an ahead portion, an astern portion, two interleaving seals between said portions, a fluid chamber common to said seals, and means whereby the fluid entering said chamber is conducted to the ahead portion. 70

3. In a reversing turbine, an ahead portion, an astern portion, two interleaving seals between said portions, a fluid chamber on the turbine rotor common to said seals and means whereby the fluid entering said chamber is conducted to the ahead portion. 75

4. In a reversing turbine, an ahead portion, an astern portion, two interleaving seals between said portions, a fluid chamber 80 on the turbine rotor common to said seals, and a fluid conduit in the turbine casing communicating with said chamber whereby the fluid entering said chamber is conducted to an operative point of the ahead portion. 85

5. In an elastic fluid turbine, primary nozzles, buckets coöperating therewith to produce rotation in one direction, secondary nozzles, buckets coöperating with said secondary nozzles to produce opposite rotation, 90 a rotor carrying said buckets, a fluid chamber in said rotor, seals located between said rotor and the portion carrying said nozzles, and means whereby the fluid entering said chamber is conducted to an effective portion 95 of the turbine.

6. In an organized turbine having ahead and astern stator portions and ahead and astern rotor portions, an annular fluid conduit between the respective stator portions, nozzles communicating with said conduit, a chamber in the rotor between the ahead and astern portions, and seals between the rotor and stator on each side of said chamber. 100

7. In an organized turbine having ahead and astern stator portions and ahead and astern rotor portions, an annular fluid conduit between the respective stator portions, nozzles communicating with said conduit, a leakage-fluid chamber in the rotor between 110 the ahead and astern portions, seals between the rotor and stator on each side of said chamber, and a conduit in the stator for leading the steam collected in said chamber to an effective portion of the turbine. 105

8. In an organized ahead and astern turbine having the respective portions of the rotor mounted on a common shaft, a casing having two exhausts, an annularly-arranged steam conduit adjacent to the high-pressure 120 end of each portion of the rotor, stationary nozzles communicating with said conduit, a leakage fluid chamber located in said rotor and interleaving seals at either side of said chamber between the peripheral faces of said 125 nozzles and the rotors. 115

9. In an elastic fluid turbine, a stator, a rotor, an annular fluid passage formed integrally with said stator and communicating with fluid supply nozzles, a leakage fluid 130

chamber in the rotor adjacent to said nozzles and means for conducting leakage fluid therefrom to a working portion of the turbine.

10. In an elastic fluid turbine, an ahead portion, an astern portion, a seal between said portions and means whereby the fluid escaping from either of said portions through said seal is conducted to an operative point of the turbine.

11. In an elastic fluid turbine, an ahead portion, an astern portion, two interleaving seals between said portions, a fluid chamber common to said seals and means whereby the fluid entering said chamber is conducted to a working portion of the turbine.

12. In a reversing turbine, an ahead portion, an astern portion, two interleaving seals between said portions, a fluid chamber on the turbine rotor common to said seals and means whereby the fluid entering said chamber is conducted to a working portion of the turbine.

13. In a reversing turbine, an ahead portion, an astern portion, two interleaving

seals between said portions, a fluid chamber 25 on the turbine rotor common to said seals, and a fluid conduit in the turbine casing communicating with said chamber whereby the fluid entering said chamber is conducted to an operative point of the turbine.

14. In an elastic fluid turbine, a stator, a rotor, a fluid-supply passage communicating with fluid-supply nozzles, a leakage fluid chamber in the rotor adjacent to said nozzles and means for conducting leakage fluid therefrom to a working portion of the turbine.

15. In an elastic fluid turbine, a stator, a rotor inclosed within said stator, a leakage fluid chamber located within said rotor, and means for conducting leakage fluid therefrom to a working portion of the turbine.

In testimony whereof, I have hereunto subscribed my name this 17th day of August, 1904.

GEO. WESTINGHOUSE.
